UNITED STATES PATENT OFFICE.

LEWIS HALLOCK NASH, OF BROOKLYN, ASSIGNOR TO THE NATIONAL METER COMPANY, OF NEW YORK, N. Y.

OSCILLATING WATER-METER.

SPECIFICATION forming part of Letters Patent No. 320,579, dated June 23, 1885.

Application filed April 26, 1884. Renewed January 24, 1885. (No model.)

To all whom it may concern:

Be it known that I, LEWIS HALLOCK NASH, a citizen of the United States, residing at Brooklyn, in the county of Kings and State of New York, have invented new and useful Improvements in Oscillating Water-Meters, of which the following is a specification.

In an application for a patent filed by me December 18, 1883, under Serial No. 114,916, I have described a water-meter in which an eccentrically moving piston is controlled by co-operating studs and a radial abutment, which divides the inflow from the outflow, upon which the piston swings in its movement to divide the chamber-case into receiving and discharging spaces; and I do not, therefore, broadly claim herein such means for controlling an eccentrically-moving piston.

The object of my present improvement is to increase the delivering capacity of the meter, to provide an effective joint of the piston with the abutment, to provide a free passage of the water into and from the piston-chambers at each side of its bearing upon the radial abutment upon which the piston has a sliding swinging movement, and to provide for the yielding of the piston to free itself of an obstruction entering the case.

My improvements consist of an eccentrically-moving piston having two or more concentric rings connected by a web, combined with an inclosing-case having two or more ring-projections, and a radial abutment extending from the inner ring projection to the side of the case, to divide the inlet ports from the outlet ports, whereby each ring of the piston performs a dividing action within the corresponding annular space of the case, and the total displacing action of the piston is thereby increased, each receiving and discharging space of the case having corresponding inlet and outlet ports.

My invention also embraces a novel means of forming a joint of the piston with the radial abutment, to prevent the passage of the water at the point upon which the piston swings from the inlet to the outlet in the eccentric movement of the piston; also, my invention consists in controlling the movements of the piston by a yoke or link connecting it with the case, having a yielding bear-

ing, whereby the piston has capacity for yielding to prevent its stoppage from obstruction; and my invention further consists in constructing the piston with a slot bearing upon the abutment, supplemented by passages or ports in the wall on each side of said slot, for the purpose of giving a free passage of the water while having the bearing-slot for the piston.

Referring to the accompanying drawings, Figure 1 represents a vertical section of a meter embracing my improvements, taken on the line Z Z of Fig. 2, which represents a top view of the meter with the upper half of the case removed, showing the piston in plan. Fig. 3 represents a horizontal section of the meter, taken on the line y y of Fig. 1. Fig. 4 represents a side view of the piston, showing the side slot supplemented by the water-passages. Fig. 5 represents an enlarged detail of the loop or link connection of the piston-controlling studs and its yielding bearings. Fig. 6 represents a detail showing a modification of the wall-ports of the piston.

The meter-case A is preferably of cylindrical form, closed by a head, C, and having two or more interior concentric ring-projections, A² A³, about equally placed within the case, to divide it into separate chambers J and K, and open at their upper ends. The case has a radial abutment, A', which extends from the inner ring-projection, A², to the side wall of the case, to divide the inlet from the outlet ports, and is of a height equal to the ring-projections.

The piston consists of two or more concentric rings, B B³, connected by a web, B', which forms its upper closed end, as shown in Fig. 1, and they are so disposed relatively with the case-ring projections as to form a continuous joint-contact therewith and with the inner wall of the case, whereby to divide the case-chambers and the piston into receiving and discharging spaces. The piston-web is extended to form an externally projecting arm, B², of suitable length and form to make a joint with the top of the abutment and the case. This arm extends through an opening in the wall of the case and into a chamber, r, formed within the case, and is of a form adapted to make a joint-contact with the edges s s of the opening in the case-wall in all positions of the

movement of the piston to prevent the passage of the water from one side of the abutment to the other at this portion of the case, while the web of the piston forms a joint with the 5 upper open ends of the ring-projections and the abutment, between which and the top head it is fitted to operate. One of the rings, as B³, has a side slot, e, adapted to allow the piston to move over the abutment and form a 10 guide-bearing thereon, the edges f f of said slot forming said bearing and extending from the open end to the web of the piston. Co-operating with this guide-bearing formed by the slot e in controlling the movement of the 15 piston, I provide its web with a depending stud, F', and the lower head of the case with a similar stud, H', and connect them by a link or yoke, L, having interior bearings, e' e'', supported upon an intervening spring, m, where- 20 by to provide a positive connection, which will allow the piston to yield in case a hard substance should enter between its rings and the case-rings in the flow of the water, and thus prevent the stoppage of the meter. The inlet-passage I 25 on one side of the radial abutment conveys water to the inlet-ports I² I⁴ in the lower cylinder-head and to the port x in the case-wall, while the discharge of the water is effected through corresponding ports, O² O⁴, in the lower 30 cylinder-head, and the port x' in the case-wall on the opposite side of the abutment to the outlet-passage O. The outer case-ring projection, A³, has ports x² x³ on each side of the abutment, which form communication with 35 the annular spaces J K, both inside and outside of said ring-projections, for the free flow of the water. The interior projecting ring, B, of the piston has a slot, v, whereby it is allowed to pass over the abutment in the eccentric 40 movement of the piston and permit a free flow of water into and out of its chambers.

The exterior ring-projection, B³, has provision for inflow and outflow of the water, which consists of a series of holes, v², formed in 45 said ring-projections on each side of the slot e, as shown in Fig. 4, whereby the piston-guide-bearing edges f f of the slot are used with the advantage of a free flow of water at this point along the full height of the piston, 50 and with such arrangement of ports and passages the piston works perfectly free of resisting suction.

I have shown and described a meter constructed with a piston having an end web; 55 but the web may be arranged to divide the piston into upper and lower chambers, and the case formed with upper and lower ring projection, the functions and operations of all the parts being the same.

60 The connecting-shaft 1 of the registering mechanism is journaled in the upper case-head, having at its inner end a crank-arm, 2, adapted to bear upon and be driven by a pin, F, on the piston-web, while the outer end of 65 said shaft extends through the case-head C, and carries a pinion, b, which meshes with a gear-wheel, a, on the shaft d, which is stepped

in the head, and, passing through the stuffing-box of a cover, D, has a gear-wheel, c, which engages with and operates any suitable registering mechanism by which the revolutions of 70 the piston are indicated.

In the operation of the meter, the piston being in the position shown in Fig. 2, the water enters through the inlet-passage I, 75 thence into the annular outer space, J, through the ports I² and x and v², and into the inner annular space, K, of the case through the ports I⁴ and x², and presses against the inner surfaces of the piston-rings B B³, and forces the 80 piston in the direction of the arrow 3, while the water discharges through the corresponding ports on the opposite side of the abutment, the inlet and outlet currents being indicated by the arrows in Fig. 3. When the piston has commenced to move to the position shown in Fig. 3 the water will enter the case-chambers outside of each ring of the piston through the same ports, and, pressing against their exterior surfaces, continue to force the 85 piston in the same direction, while the water discharges from the opposite side of the case-chambers through the corresponding ports on the opposite side of the abutment, driving the piston into the position shown in Fig. 3. In 90 this position the exterior pressure of the water alone acts upon the piston, but as the piston passes this position the water again enters the interior receiving spaces of the piston through the ports I² I⁴ of the case-head and 95 the ports v v² of the piston-rings, continuing the movement of the piston, while the water escapes from the discharging spaces of the piston through the corresponding outlet-ports on the opposite side of the abutment. In this 100 continuous movement of the piston it maintains a perpetual division of the case-chambers into receiving and discharging spaces, and in the eccentric movement it pushes forward the crank-arm 2, and thus operates the 105 registering-gearing (which is not shown) to register the movement of the piston.

While I have shown the piston-slot supplemented with drilled wall-perforations, the edges of the slot may be notched and effect 110 the same purpose; or I may form vertical passages v² in the piston-walls on each side of its bearing-edges f f, as seen in Fig. 6, which passages open into the cylinder-ports I² O², and into the receiving and discharging 115 spaces on each side of the abutment, the said vertical wall-passages opening at v² on each side of the bearing-edges f f into the said spaces, and thus allow the water to pass into and from these spaces the full height of the piston on its 120 inside and on its outside.

In another application for a patent filed by me bearing even date herewith I have shown, described, and claimed a piston having an external arm, which serves the functions of forming a guide upon which the piston swings and a joint to prevent the flow of the water through the abutment-opening. In the present construction the guide upon which the piston 125

swings is formed by the contact of the edges *ff* of the piston side slot, *e*, with the opposite sides of the abutment *A'*, and the arm *B²* forms the joint with the top edge of the abutment, and with the case-chamber at the sides *s s* of its opening end.

In the position shown in Fig. 2 the joint is at both points *s s* of the case-wall with the opposite sides, *b² b³*, of the arm *B²*, and as the movement of the piston changes, the position of its arm also changes, so that its end, being enlarged or having a T-shaped head, will form by its points *b³ b³* a joint with one or the other side *s²* of the wall-chamber *r*, so that as the piston is guided by the abutment and the co-acting studs the piston-arm makes the joint, as stated.

It is obvious that a single ring-piston may be used with the side slot, *e*, the wall-ports *v²*, and the guide-edges *ff*.

I claim—

1. The combination, with a meter-case having two or more concentric ring-projections and a radial abutment extending from the inner one to the side of the case, of an eccentrically-oscillating piston composed of two or more concentric rings, the outer one forming a guide-bearing upon said abutment, and inlet and outlet head-ports opening into said concentric ring-projections, having direct communication with the inlet and outlet passages, substantially as described, for the purpose specified.

2. The combination, with a meter-case having inlet and outlet ports divided by a radial abutment, as described, and having two or more ring-projections, the outer one forming a guide-bearing upon said abutment, of an eccentrically-oscillating piston composed of two or more rings having an external arm adapted to form a joint with the radial abutment at every point in the movement of the piston, and means, substantially such as described, co-operating with said abutment for controlling the piston in its path, for the purpose specified.

3. The combination, with a meter-case having inlet and outlet ports divided by an abutment, as described, of an eccentrically-oscillating piston having a side slot adapted to form a guiding-bearing upon said abutment within the chamber of the case, and having an external arm adapted to form a joint with the abutment outside of the chamber-case, and means, substantially such as described, for controlling the piston in its path, for the purpose specified.

4. The ring-piston having a side slot, *e*, supplemented by perforations or openings on each side of said slot, and an external joint-forming arm, combined with a case having inlet and outlet ports divided by an abutment, and

the connected controlling-studs, substantially as described, for the purpose specified.

5. The combination, in a water-meter, of a case having inlet and outlet ports divided by an abutment, as described, of an eccentrically-oscillating ring-piston having a side slot and a controlling connection with the case, consisting of the fixed interior case-stud, and a coacting piston connected by a yielding bearing, substantially as described, for the purpose specified.

6. The combination of the case having inlet and outlet ports divided by an abutment and by ring-projections, as described, with a piston having two or more eccentric rings, the outer ring having the side slot, *e*, and ports or passages *v²* in its wall and the inner ring having the wall-ports *v*, and means, substantially such as described, for controlling the piston.

7. The combination of the case *A*, having inlet and outlet ports divided by an abutment, with a ring-piston having a side slot, *e*, adapted to form a guide, *ff*, upon said abutment, provided with wall ports or passages on each side of said guide, as herein set forth.

8. The case having the head-ports and the outer wall-ports, *xx*, divided by an abutment, as described, combined with a ring-piston having the wall-slot *e*, adapted to form a guide, *ff*, upon said abutment, and the wall-ports *v²*, arranged as and for the purpose described.

9. The water-meter herein described, consisting of the case *A*, having the inlet and outlet ports, a radial dividing-abutment, *A'*, for said ports, and two or more concentric ring-projections, *A² A³*, a ring-piston having a transverse web, *B'*, an external arm, *B²*, two or more concentric ring-projections, *B B³*, the connected studs *H' F*, the said rings *A³ B B³* and the case-wall having the ports *x x' x² x³* and *v v*, and the said piston operating the registering-gearing by the pin *F*, all constructed and arranged for operation, substantially as described.

10. The combination of the case *A*, having inlet and outlet ports and a dividing-abutment, with a ring-piston having a transverse web, the wall-slot *e*, adapted to form a guide, *ff*, upon said abutment, a radial arm, *B²*, and a case-chamber, the said arm being adapted to form a joint with the said chamber-walls in the eccentrically-oscillating movement of the piston upon the abutment, substantially as described, for the purpose specified.

In testimony whereof I have hereunto set my hand in the presence of two subscribing witnesses.

LEWIS HALLOCK NASH.
